UNITED STATES PATENT OFFICE.

WILLIAM J. FLEMING, OF NEW YORK, N. Y.

DESIGN FOR A SKIRT-SUPPORTER.

SPECIFICATION forming part of Design No. 28,115, dated January 4, 1898.

Application filed November 9, 1897. Serial No. 657,984. Term of patent 31 years.

To all whom it may concern:

Be it known that I, WILLIAM J. FLEMING, a citizen of the United States, residing in the city of New York, in the county and State of New York, have invented and produced a new and original Design for Skirt-Supporters, of which the following is a specification.

The design consists in the shape or configuration of the skirt-supporter which is illustrated in and may be seen from the accompanying drawing, showing a perspective view of a skirt-supporter.

As shown, this consists of a thin flat plate A, forming the body of the supporter, having straight parallel sides 11, which are connected by curved lines 22, bounding the lower corners, with the base-line 3. From the upper edge of the plate A projections B B extend upwardly in the same plane as the plate A and then outwardly and downwardly in a plane parallel or nearly parallel to the plane of the plate A, so as to form the belt hooks or loops C C. The side lines 4444 of the projections B B are parallel, while the side lines 5555 of the hooks C C gradually converge as they extend downward, so as to form tapered rounded points. From the lower part of the space between the projections B B a

tapered slot extends downward into the body of the plate A, terminating in an enlarged 30 opening E of a diameter greater than the width of the narrowest part of the slot D. The side lines 66 of the slot E are similar curves, which, starting from the lower termini of the inner side lines 44 of the projections B B, 35 gradually converge until they meet the bounding-line 7 of the opening E, which is circular.

The design is pleasing to the eye, inasmuch as it presents a graceful combination of lines, 40 and at the same time its form and proportions give an attractive impression of solidity and security.

Having thus described my invention, what I claim as new, and desire to secure by Letters 45 Patent, is—

The design for a skirt-supporter, substantially as herein shown and described.

In testimony whereof I have hereunto subscribed my name this 6th day of November, 50 A. D. 1897.

WM. J. FLEMING.
